(57) **CLAIM**

The ornamental design for a screen protector applicator for an electronic device, as shown.

DESCRIPTION

FIG. 1 is a front perspective view of a screen protector applicator for an electronic device embodying the new design;

FIG. 2 is a rear perspective view thereof;

FIG. 3 is a rear elevational view thereof;

FIG. 4 is a front elevational view thereof;

FIG. 5 is a left side elevational view thereof, the right side elevational view being a mirror image of the left side elevational view; and,

FIG. 6 is a bottom plan view thereof, the top plan view thereof being a mirror image of the bottom plan view.
